ABSTRACT OF THE DISCLOSURE

An arc radiation torch having a high pressure arc established between two electrodes located adjacent the ends of the torch and forming an arc chamber therebetween and cooling means comprising means for bleeding a small quantity of liquid into the chamber, which liquid is spread as a thin film over the inner surface of the chamber for continuously cooling said chamber. The liquid is spread by gas which is in a swirling flow pattern such that it also constricts the arc.

This invention relates to arc radiation sources, and more particularly to a novel method and means for cooling such sources.

The invention provides an arc radiation source comprising a transparent elongated envelope or tube; electrodes located adjacent the ends of said envelope; means for energizing a high pressure arc in said envelope between said electrodes, and cooling means comprising means for continuously bleeding liquid into said envelope in sufficient quantity only to keep wet the inner surface of said envelope; and means for spreading such liquid only over such inner surface in a thin film while simultaneously constricting said arc along a lineal path between the electrodes.

While prior radiation sources achieve a relatively long, high current density arc, they are not without their problems; the most serious problem is that of deterioration of the transparent envelope or tube forming the arc chamber. Such deterioration is caused primarily by the heat generated by the arc.

In one method of attempting to solve the deterioration problem in prior arc radiation sources, a fluid such as water, was passed over and around the outer surface of the transparent tube. But such method does not directly remove the heat from the inner surface where it is being generated.

It is, therefore, the principal object of the present invention to provide an arc radiation source having a useful life that dramatically and far exceeds that of the prior art by virtue of superior cooling advantages.

In accordance with the invention, there is provided a method of cooling an arc radiation source in which a lineal high pressure arc is energized along the axis of a transparent elongated envelope or tube, which comprises continuously spreading only a thin film of liquid over the inner surface of said envelope. The thin film of liquid is formed over substantially the entire inner surface of the transparent envelope or tube by utilizing the swirling gas flow pattern of an arc constricting gas to force the liquid only over such inner surface. While distilled water is the preferred liquid, other transparent liquids such as tap water may also be used.

As shown in the accompanying drawing in which the single figure is a view mainly in longitudinal cross section of an arc radiation source embodying the invention, a transparent tube or cylindrical envelope 10, composed of quartz, for example, is supported adjacent its ends in terminal members 12 and 14, respectively, composed of copper. Such members are hollow, their chambers 16 and 18 being continuous with the elongated chamber 20 of the tube 10.

The members 12 and 14 are provided with electrodes 22 and 24 located concentrically with respect to the longitudinal axis of the tube 10 for carrying a lineal high pressure arc when such electrodes are energized by connection to a suitable source of electric power (not shown).

The member 14 also is provided with gas inlet ports 26, as well as cooling liquid inlet ports 28 that extend between the inner wall 30 of chamber 18 and annular cooling water distribution manifold 32 and gas distribution manifold 34, respectively. The liquid inlet ports 28 are substantially equally spaced and their axes are arranged in frusto-conical surface of revolution that is concentric with the longitudinal axis of the arc chamber 20, being inclined so as to bleed cooling liquid into such chamber.

The gas inlet ports 26 are substantially equally spaced with their axes located in a plane that is perpendicular or transverse to the longitudinal axis of the chamber 20, which plane is positioned behind the liquid inlet ports 28. The axes of the gas inlet ports are tangent to a common circle that is concentric with such axis, so as to give the gas a swirling flow pattern throughout the chamber 20, which not only constricts the arc, but also spreads the cooling liquid from the ports 28 in a thin film over substantially the entire inner surface of the tube 10.

The member 12 is provided with an annular outlet 36 for discharge of the gas and the liquid film from the arc chamber 20. The electrode 22 (anode) is cooled by circulating water through inlet and outlet passages 38 and 40. Similarly electrode 24 (cathode) is cooled by circulating water through inlet and outlet passages 42 and 44. The cathode 24 is insulated from the rest of the assembly by a ceramic or plastic sleeve 25. Body 46 is located between members 12 and 14 and is provided with a high reflective inner surface 48 that is semi-elliptical, as shown; or completely elliptical as shown in the copending application of Anderson and Jackson, filed concurrently herewith, for Continuous Wave Lasers.

A suitable arc gas such as the inert gases of argon, xenon and krypton, is introduced into the arc chamber 40 through the gas inlets so that the gas enters the chamber in a swirling fashion. These inert gases have a high atomic number which yields a high probability of electronic transition that is necessary for good radiation. The swirling gas flows in such swirling fashion, near the arc 45 along the axis of the chamber from whence it discharges. This flow pattern creates a lineal highly intense arc of high current density.

An important feature of this invention is that the arc gas is utilized to spread the thin film of liquid coolant over substantially the entire inner surface of the tube.

The liquid, which may be tap water, or may be as preferred—distilled water, is allowed to "seep" (1/2 g.p.m.) into the arc chamber, so that the swirling gas readily spreads the liquid into a thin uniform film. Such uniformity is desirable to prevent distortion of the radiation rays. Uniformity is also increased by proper selection of the number of ports, and by directing or slanting the ports toward the tube.

As an alternative to the use of water, a liquid suitable for absorbing unwanted radiation rays may be used. For example, a sodium chromate or a sodium nitrate solution may be used to absorb ultraviolet rays.

In an experiment showing advantages of the invention, a radiation source of the type depicted was tested with and without the film of liquid (distilled water) being spread over the inner surface of the transparent tube. At an electrical input of about 7.5 kw. a radiation output of 409 watts (5.52%) was recovered in an ink-water solution (for radiation measuring purposes) with water on. Without the water, an output of 464 watts was recovered. When the water was turned off, the transparent tube as-

sembly failed within 30 seconds. With the water, a run of about 10 minutes was made. However, the quartz tube would last indefinitely. Thus at a small loss of radiation, the thin film of water effectively cools the transparent tube assembly, and substantially increases the useful life thereof.

What is claimed is:

1. An arc radiation source comprising a transparent elongated envelope, electrodes located adjacent the ends of said envelope for establishing a high pressure arc therebetween, and cooling means comprising means for continuously bleeding liquid into said envelope in sufficient quantity only to keep wet the inner surface of said envelope, means for spreading such liquid only over such inner surface in a thin film while simultaneously constricting said arc along a lineal path between said electrodes and means for discharging said liquid from said envelope.

2. An arc radiation source as defined by claim 1, including hollow means connected to one end of said envelope with the inner wall thereof continuous with that of the envelope, said means being provided with liquid inlet ports for bleeding the cooling liquid for such film toward such inner surface of the envelope, and with gas inlet ports located behind such liquid inlet ports for directing arc constricting gas in a swirling flow pattern while simultaneously spreading the liquid film over substantially the entire inner surface of the envelope.

3. An arc radiation source as defined by claim 2, wherein said discharge means is located at the other end of said envelope, and is provided with an annular outlet for the liquid of such film as it leaves the inner surface of the envelope, as well as for such arc constricting gas.

4. An arc radiation source as defined by claim 2, in which such gas inlet ports are substantially equally spaced

and are arranged with their axes located in a common plane that is perpendicular to the longitudinal axis of the envelope, the axes of said ports being tangent to a common circle that is concentric with such longitudinal axis.

5. An arc radiation source as defined by claim 4, in which such liquid inlet ports are substantially equally spaced and are arranged with their axes located in a frustoconical surface of revolution that is concentric with such longitudinal axis.

6. Method of cooling an arc radiation source in which a lineal high pressure arc is energized along the axis of a transparent elongated envelope, which comprises: passing gas through the elongated envelope in a swirling flow pattern; and continuously introducing a relatively small quantity of cooling liquid into said envelope in the path of said swirling gas flow such that said gas projects the liquid against the inner surface of said envelope while spreading said liquid in a thin film over substantially said entire inner surface.

10 7. Method as defined by claim 6, in which said liquid film is substantially transparent, the envelope is composed of quartz, and the gas is selected from the class consisting of argon, xenon and krypton.
